No. 728,363.

PATENTED MAY 19, 1903.

W. J. CALKINS.

VEHICLE TONGUE SUPPORTER.

APPLICATION FILED JUNE 4, 1902.

NO MODEL.

UNITED STATES PATENT OFFICE.

WALTER J. CALKINS, OF ROCKYFORD, COLORADO, ASSIGNOR OF ONE-
THIRD TO ELMER COMER, OF ROCKYFORD, COLORADO.

VEHICLE-TONGUE SUPPORTER.

SPECIFICATION forming part of Letters Patent No. 728,363, dated May 19, 1903.

Application filed June 4, 1902. Serial No. 110,204. (No model.)

To all whom it may concern:

Be it known that I, WALTER J. CALKINS, a citizen of the United States, residing at Rockyford, in the county of Otero and State of Colorado, have invented a new and useful Vehicle-Tongue Supporter, of which the following is a specification.

The invention relates to improvements in vehicle-tongue supporters.

10 The object of the present invention is to improve the construction for connecting horses with vehicle-tongues, and to provide a simple, inexpensive, and efficient device capable of being readily applied to a horse and adapted to relieve the neck of the animal of the weight of the tongue and to enable the tongue to be supported by the withers of the animal.

15 The invention consists in the construction and novel combination and arrangement of parts hereinafter fully described, illustrated in the accompanying drawings, and pointed out in the claims hereto appended.

20 In the drawings, Figure 1 is a side elevation of a tongue-support constructed in accordance with this invention and shown applied to a horse. Fig. 2 is a front elevation of the device, illustrating its arrangement with relation to the breast-strap. Fig. 3 is a detail view of the device.

25 30 Like numerals of reference designate corresponding parts in all the figures of the drawings.

35 40 1 designates the body portion of the tongue-support, consisting of a piece of stout leather or other suitable material, tapered from the center to the ends and bowed longitudinally to conform to the configuration of the back of the animal at the withers. The body portion has a straight front edge when arranged as shown in Fig. 3, and its rear edge is curved

45 to form the oppositely-tapered portions, and the said body portion is provided with central longitudinal incisions 2 and 3, located at the central portion of the tongue-support and adapted to permit the central portion of the body of the support to be arched transversely of it to conform to the configuration of the back of the animal. The body of the tongue-support is braced by straps or bars 4, of metal, 50 located at opposite sides of the center and adapted to retain the central portion of the

support in its bowed or arched form, and these metal straps or bars are curved and riveted or otherwise secured to the body of the support. The body of the support is provided with an interior lining 5, of felt or other suitable material, to prevent it from chafing the withers of an animal; but it may be padded in any other suitable manner.

55 60 65 70 75 80 85 90 95 The body of the tongue-support is provided with a central buckle 6, and it has straps 7, secured to its ends. The buckle is adapted to receive the back-strap of a harness and the straps 7, which are designed to be connected with a breast-strap 8, have their upper terminals 9 split and forked or diverged, as shown in Figs. 1 and 3. The forked portions of the straps 7 are stitched or otherwise secured to the end portions of the body, adjacent to the front and rear edges thereof. The straps 7 are provided between their ends with buckles 10 and have their lower or outer portions bent upon themselves to form loops 11, which pass through rings 12 of hames 13 and which receive and support rings 14. The rings 14 are designed to be connected with the breast-strap 8. In applying the device to an animal the body of the tongue-support is arranged in rear of the hames, as indicated in Fig. 1 of the drawings, and the straps 7 are extended downward through the lower hame-rings and through the rings 14 and are then passed upward back through the hame-rings and are buckled above the latter. The breast-strap, which is connected in the usual manner with the tongue of a vehicle, is attached to the rings 14, and the weight of the tongue is supported by the device, which is arranged at the withers of the animal, whereby its neck is relieved of the weight of the tongue.

It will be seen that the device is exceedingly simple and inexpensive in construction, that it is adapted to be readily applied to an animal, and that it is capable of effectively relieving the neck of the same of the weight of the tongue.

What I claim is—

1. A device of the class described comprising a body designed to be arranged in rear of a horse-collar and having inclined front edges to fit the rear edges of the latter and

provided with central incisions forming an arched portion adapted to conform to the withers of the horse, transverse braces connecting the cut portions of the body and 5 adapted to retain the shape of the central portion, and straps depending from the ends of the body portion and adapted to be directly connected with a breast-strap, substantially as described.

- 10 2. In a device of the class described, the combination with a horse-collar, and a pair of hames provided with rings, of a tongue-supporting device comprising a body having downwardly-tapered side portions and pro-
15 vided with inclined front edges to fit the rear edges of the collar, said body being also provided with longitudinal cuts or incisions forming front and rear openings in order to

form an arch to fit over the withers of the horse, bars or braces arranged transversely 20 of the cuts or incisions and located at opposite sides of the body and spacing the severed portions of the same, side straps extending downward from the sides of the body and passing through the rings of the hames, means 25 for directly connecting the side straps with a tongue, and a similarly - arranged buckle mounted upon the body at the top thereof, substantially as described.

In testimony that I claim the foregoing as 30 my own I have hereto affixed my signature in the presence of two witnesses.

WALTER J. CALKINS.
